UNITED STATES PATENT OFFICE.

JOSEPH R. DEW, OF KNOXVILLE, TENNESSEE.

FRUIT-DRIER.

SPECIFICATION forming part of Letters Patent No. 320,543, dated June 23, 1885.

Application filed May 12, 1884. (No model.)

To all whom it may concern:

Be it known that I, JOSEPH R. DEW, a citizen of the United States, residing at Knoxville, in the county of Knox and State of Tennessee, have invented a new and useful Fruit-Drier, of which the following is a specification, reference being had to the accompanying drawings.

This invention has relation to fruit-driers, and is designed as an improvement on the fruit-drier described and shown in Letters Patent No. 284,726, granted to me September 11, 1883; and it consists in the construction and novel arrangement of parts, as will be hereinafter fully described, and particularly pointed out in the claims.

Figure 1 is a view in perspective of a fruit-drier embodying my improvements. Fig. 2 is a vertical longitudinal section on the line xx , Fig. 1. Fig. 3 is a transverse vertical section on the line yy in Fig. 1. Fig. 4 a is vertical longitudinal section on the line zz , Fig. 1. Fig. 5 is a view in perspective of one of the fruit-drawers. Fig. 6 is a view in perspective of one of the bleacher frames; and Fig. 7 is a detail view of the sulphur-burner.

Referring by letter to the accompanying drawings, A designates the furnace; B, the smoke-stack, and C the boiler of the fruit-drier. The boiler C is preferably rectangular in form, and has four steam-pipes, D, one at each corner, connected at their upper and lower ends by horizontal steam-pipes E E', and connected also by end walls, F F', to form the casing or frame for the steam-boxes G, the fruit-drawers, and the bleacher. The steam-boxes G have openings H at their corners, and communicate through these openings with the steam-flues D. The bottoms of the steam-boxes G are drawn up at their centers by thimbles I, connecting with their top walls, to cause the water of condensation to run to the corners of the steam-boxes, and back through the steam-pipes D to the boiler.

K designates the water-pipe, and K' the funnel through which water is supplied to the boiler.

L is the steam-escape pipe, and M the water-outlet covered by a screw-cap. The water-outlet M is located in the upper horizontal steam-pipe, E, and the steam-escape pipe L

also connects with this pipe E, and extends down over the funnel K'.

The fruit-drawers N consist of the longitudinal wooden slats a, the transverse wooden slat b, the grooved metal end slats, c c, and the metal side walls, d. The fruit-drawers N are provided with central wire loops f, which are passed up through the thimbles I, and wedges g are passed through their projecting ends to suspend the fruit-drawers below the steam-boxes G.

The bleacher O consists of the two half parallelogram frames P P, provided with flange-walls P' for closing the space between two of the steam-boxes G, and a series of inwardly-projecting rectangular wires, Q, upon which the peeled, cored, and sliced fruit is hung and every side of the fruit exposed and subjected to sulphur smoke from the sulphur-burner R, suspended from the thimble I in the steam-box that forms its bottom by a pin, S, passed through perforations in the pipe R' of the burner R. The bleacher-frames P P are held in place by the arms h h of a pivoted rod, U, having bearings on the top of the steam-box which forms the top of the bleacher.

Any number of steam-boxes and fruit-drawers may be used with the single boiler having the steam-pipes arranged as hereinbefore described.

The steam ascends the corner pipes, and is distributed equally and freely to the steam-boxes, heating them quickly. The corner pipes give greater strength to the structure than in my former construction. The fruit dries uniformly and quicker. The spaces beneath the fruit-drawers are left open so that the air carries the vapor arising from the fruit away and prevents it from wetting other fruit. The drawers being suspended are easier to handle and may be more conveniently applied, and the bleacher is more convenient than the common side-box bleachers.

Having thus fully described my invention, what I claim as new, and desire to secure by Letters Patent of the United States, is—

1. In a fruit-drier, the combination, with the boiler and the corner steam-pipes connected by horizontal steam-pipes, of the herein-described steam-boxes communicating at their corners or ends with the corner steam-

pipes and having their bottoms drawn up or raised at their centers, whereby the water of condensation is caused to run to the corners of the steam-boxes and back through the 5 steam-pipes to the boiler, as set forth.

2. In a fruit-drier, the combination, with the steam-boxes having the thimble or opening, of the fruit-drawers provided with a loop or extension which passes through the thimble 10 or opening, and means, substantially as described, for detachably securing the loop or extension in the opening, for the purpose set forth.

3. In a fruit-drier, the combination, with 15 the steam-boxes having a central opening or thimble, of the fruit-drawer having its side walls clasping the sides of the boxes, a loop or equivalent device passing through the opening or thimble of the boxes, and means, substantially as described, for securing the loop in place to hold the drawers against the under side of the boxes, as set forth.

4. The combination, with the steam-boxes, of the bleacher-frames normally closing the 25 space between the boxes, and a pivoted rod having arms for holding the bleacher-frames in place, as set forth.

5. The combination, with the boiler, of the steam-boxes arranged in a series one above the 30 other, the walls F F', connecting the ends of the boxes and openings through the walls to allow communication with the boxes, semi-cylindrical strips fitted to the outside of the walls over the openings so as to form steam-pipes D, and corresponding strips fitted to the 35 walls at the top and bottom, forming steam-pipes E E', which communicate with the ends of the pipes D, arranged and combined as set forth.

40 6. In a fruit-drier, the combination, with the boiler, and a funnel communicating therewith and located on the outside of the boiler, of the steam-boxes connected together by the end walls to form the casing or frame for the 45 boxes, the corner steam-pipes fitted to the outside of the end wall and communicating with the boxes, the horizontal steam-pipes connecting the vertical corner pipes, and the water-escape pipe arranged on the outside of 50 the end wall of the casing above the funnel and connecting with the top horizontal steam-pipe, so that the water of condensation escaping from the water-pipe will drip into the funnel, for the purpose set forth.

7. In a fruit-drier, the combination, with the 55 boiler, and the funnel for supplying water to the same located on the outside of the boiler, of the steam-boxes, the steam-pipes connecting with the boiler and delivering steam to the boxes, and the water-escape pipe L, connecting 60 with the steam-pipes and located in a vertical line on the outside of the boxes above the funnel, the lower end of the escape-pipe being turned up or provided with an elbow, so that the water of condensation escaping from the 65 latter will drip into the funnel and return to the boiler, as set forth.

8. In a fruit-drier, the combination, with the 70 steam-boxes, of the herein-described bleacher consisting of two frames independently removable, and each of which has a series of inwardly-projecting wires or hangers upon which the fruit is suspended, as set forth.

9. In a fruit-drier, the combination, with the 75 steam-boxes, of the herein-described bleacher normally closing the space between the boxes, and provided with a series of wires or hangers upon which the fruit is suspended, for the purpose set forth.

10. In a fruit-drier, the combination, with 80 the steam-boxes having a central opening or thimble, of the bleacher-frames fitting in the space between the boxes, and the sulphur-burner having its pipe projecting up through the thimble or opening into the bleaching- 85 chamber, as set forth.

11. In a fruit-drier, the fruit-drawer N, consisting of the wooden slats *a* and *b*, grooved metal end slats, *c c*, and metal side walls, *d*, substantially as specified.

12. In a fruit-drier, the combination, with 90 the steam-box G, having the central thimble, *I*, of the fruit-drawer N, provided with the loop *f*, and the wedge *g*, substantially as specified.

13. In a fruit-drier, the combination, with 95 the steam-boxes, of the bleacher-frames P, having flange-walls *P'* and angular wires *Q*, and the sulphur-burner *R*, secured to the lower steam-box and having its pipe projecting up through the thimble into the bleaching-chamber, substantially as specified.

In testimony that I claim the foregoing as my own I have hereto affixed my signature in presence of two witnesses.

JOSEPH R. DEW.
